DRESS ENSEMBLE

Herman Lipman, New York, N. Y.

Application January 13, 1954, Serial No. 28,497

Term of patent 3½ years

(CL. D3—26)

To all whom it may concern:

Be it known that I, Herman Lipman, a citizen of the United States, and a resident of the city of New York, in the county of New York and State of New York, have invented a new, original, and ornamental Design for a Dress Ensemble, of which the following is a specification, reference being had to the accompanying drawing, forming a part thereof.

Fig. 1 is a front view of the dress ensemble, showing my new design.

Fig. 2 is a rear view of Fig. 1.

Fig. 3 is a front view of the dress section of the ensemble shown in Fig. 1.

Fig. 4 is a rear view of Fig. 3.

I claim:

The ornamental design for a dress ensemble, substantially as shown.
